UNITED STATES PATENT OFFICE.

THOMAS C. BEAUMONT, OF NEW YORK, N. Y., ASSIGNOR TO THE HENRY HUBER COMPANY, OF SAME PLACE.

FLUSHING-TANK.

SPECIFICATION forming part of Letters Patent No. 533,982, dated February 12, 1895.

Application filed November 27, 1893. Serial No. 492,036. (No model.)

To all whom it may concern:

Be it known that I, THOMAS C. BEAUMONT, a citizen of the United States, residing in the city, county, and State of New York, have invented certain new and useful Improvements in Flushing-Tanks, of which the following is a specification.

This invention relates to certain improvements in flushing tanks for water closets or the like, the invention being directed to means for rendering the tank noiseless in operation, and to means for supporting and guiding the valve and overflow pipe.

Figure 1 of the accompanying drawings is a vertical longitudinal mid-section through the tank and valve. Fig. 2 is a vertical transverse section on the line 2—2 in Fig. 1, looking toward left. Fig. 3 is a fragment of Fig. 1 showing the valve lifted. Fig. 4 is a plan of the valve seat showing the valve tube in section.

Let A designate the tank or cistern; B, the flushing pipe leading down therefrom; C, the water supply pipe leading thereto; D, the float valve or cock for controlling the admission of water; D', the hush-pipe through which the water enters the tank from the float-valve; F, the float controlling the float-valve; G, the operating lever of the tank; E, the outlet valve thereof, and H the overflow pipe. Except in the particulars hereinafter stated, these parts are or may be all of any usual or known construction.

The valve E is essentially a disk having a soft seating face or packing which closes upon the annular seat *a* forming the margin of an outlet shell *b*, which extends down through the bottom of the tank, and to the lower end of which the flushing pipe B is coupled in the usual manner.

The overflow pipe H consists of a tube open at top, slightly above the normal water level, and passing down through the valve E, being formed with a downward extension lettered H' beneath the valve, and projecting into the outlet shell *b*. The overflow pipe H consequently lifts with the valve E, the two being rigidly connected. The valve E is constructed with a disk *c*, having a neck screw-

ing upon the lower end of the overflow pipe H, 50 and an outwardly projecting flange, against which flange the soft valve face or packing disk *d* of leather or rubber is clamped by a flange *e*, which is formed on the extension tube H', which tube is screwed on the lower 55 end of the overflow pipe H to form an uninterrupted continuation thereof for the descent of the overflow water.

The valve-stem I consists of a rod or wire extending down through the pipe H, and connected at its lower end to a cross-bar *f* formed within the lower end of the pipe H or the valve E. Its connection is preferably a loose one, and the stem I being thus connected centrally to the valve at its lower end, is maintained 65 concentrically within the upper portion of the tube H by means of four outwardly turned arms *g* formed on a tube *h*, which is fastened onto the valve-stem I, these arms *g* being formed with ample interstices between them 70 to permit the downflow of the overflow water. The upper end of the stem I is hooked into the lever G, the opposite arm of which is connected to the usual pull-chain *i*.

Directly over the open top of the overflow pipe H is mounted a hush-plate or disk *J*, in such position that when the valve is lifted the lifting movement of the overflow pipe will bring it against the hush-plate, so that the latter will serve to close its upper end and 80 prevent any inflow of air during the descent of the flushing water. The hush-plate is suspended so as to be loosely and freely mounted and thereby capable of being lifted, since it is encountered by the overflow pipe H in the 85 upward movement of the latter before the end of its movement is reached, so that it is lifted by the overflow pipe and remains resting on the top thereof during the time that the valve is open, as shown in Fig. 3. For thus mounting the hush-plate, it is provided with a tubular neck or stem *j*, on the upper end of which is fixed a nut or disk or other overhanging part *k*, and the tank is provided with a bracket plate or arm *J*, best shown in Fig. 2, through 90 a hole in the end of which the neck *j* freely passes, and on the top of which the head *k* rests, so that in the normal position of the

parts the hush-plate is hung from this bracket arm or support K through the medium of its neck *j* and head *k*.

In the ordinary operation of a tank of this character, namely, one in which the overflow tube passes through the outlet valve or in any other way the open overflow tube communicates with a flushing pipe, it is found that the descending stream of flushing water creates a suction which draws air down through the overflow pipe and mingles it with the stream of flushing water, so that it creates a disagreeable sucking noise in the tank. It is to overcome this noise that I have provided the hush-plate J, which when the valve is lifted serves to close the upper end of the overflow pipe shown in Fig. 3, and thereby prevents the inflow of air along with the flushing water. By constructing the plate J so that it is freely hung or suspended from the support K, it is permitted to adapt itself to the top of the overflow tube so as to make a sufficiently close joint therewith without the necessity of any fine finish for the parts, or the use of any soft packing, it not being essential to absolutely exclude all air, but simply to prevent the inrush of enough air to cause the sucking noise referred to.

I will now describe the means for guiding and centering the valve and overflow pipe. For keeping the valve concentrically in place relatively to its seat, the outlet shell *b* is formed with three internally projecting ribs *l*, as shown best in Fig. 4, which ribs form a loose engagement with the bottom of the tube *H* projecting beneath the valve, so that this tube and the valve are held properly in center. For guiding the upper part of the overflow pipe and keeping it in vertical position, the valve-stem I where it projects above this pipe passes through the tubular stem or neck *j* of the hush-plate, which itself is held in position for passing through the hole in the end of the supporting arm or bracket K. Since the valve-stem I is guided concentrically within the overflow pipe *H*, and is itself held centrally by the tubular stem *j* and its support K, it is apparent that the upper end of the overflow pipe will be thus guided or centered.

I claim as my invention the following-defined novel features, substantially as herein-before set forth, namely:

1. A flushing tank having an outlet valve with an open-topped overflow pipe passing through and movable with it, combined with a hush-plate J suspended above said pipe and having a neck *j* and head *k*, and with a supporting arm K having a hole through which said neck passes and on which said head *k* rests for suspending the hush-plate, so that the latter can be lifted when encountered by the overflow pipe upon the opening movement of the valve.

2. A flushing tank having an outlet valve with an open-topped overflow pipe passing through and movable with it, and a stem projecting up above said pipe, combined with a hush-plate J suspended above said pipe having a tubular neck *j* through which said valve stem passes, and a supporting arm for upholding the hush-plate having a guiding opening embracing said tubular neck, whereby the valve stem is concentrically guided in said opening by means of said tubular neck.

3. A flushing tank having an outlet valve with an overflow pipe passing through and movable with it, constructed with means for guiding said valve and overflow pipe at top and bottom, consisting of an outlet shell *b* having internal projecting guiding ribs *l* embracing between them the downward extension of said overflow pipe beneath the valve, the valve-stem I concentrically guided within said pipe and projecting above its upper end, a hush-plate J suspended above said pipe and having a tubular neck *j* through which said valve-stem passes and by which it is guided, and a supporting arm or bracket K from which said hush-plate is hung, having an opening embracing the tubular neck thereof.

In witness whereof I have hereunto signed my name in the presence of two subscribing witnesses.

THOMAS C. BEAUMONT.
